UNITED STATES PATENT OFFICE.

JAMES M. WINTERINGER, OF ALLEGHENY, PENNSYLVANIA.

DESIGN FOR A HALL-RACK.

SPECIFICATION forming part of Design No. 21,282, dated January 5, 1892.

Application filed December 3, 1891. Serial No. 413,941. Term of patent 7 years.

To all whom it may concern:

Be it known that I, JAMES M. WINTERINGER, a citizen of the United States, residing at Allegheny, in the county of Allegheny and State of Pennsylvania, have invented or discovered a New and Original Design for Hall-Racks, of which the following is a specification.

In the accompanying drawings, which make part of this specification, Figure 1 is a front view thereof; Fig. 2, an end view, and Fig. 3, a section on the line $x x$ of Fig. 1.

The last-named views—viz., Figs. 2 and 3—are for the purpose of showing more clearly the outline and configuration of the parts.

In the base of the rack are two cupboards, the sliding fronts 1 1 for which have two diagonal cross-strips 2 2 placed thereon and the upper and lower sets of scored wave-lines 3 3 and 4 4, and also at the intersection of the diagonal cross-strips the star 11.

The face of the rack proper consists of two duplicate side panels 5 5 and one large center panel. Each of the side panels has carv-

ing thereon, which is shown in the conventional designs at 6 6. The center panel is subdivided by raised strips 7 7 and 8 8 into four small panels 9 9. The strips 7 7 are more effective if carved, as seen at 10 10. At the intersection of the four strips is a star 11, and three similar stars 11 11 are spaced over each of the four panels 9 9.

The cornice consists of a central carved panel 12 and the two duplicate end panels 13 13, having raised strips thereon 14 14.

In Fig. 2 the panel 15 15 makes the door 35 for hanging cupboards 16 16.

I claim—

The design for a hall-rack, as herein shown and described.

In testimony whereof I have hereunto set my hand this 27th day of November, A. D. 1891.

JAMES M. WINTERINGER.
